(57) **CLAIM**

The ornamental design for a casting mold and handling frame for an assay matrix, as shown.

DESCRIPTION

FIG. 1 is a perspective exploded view of the mold for the assay matrix, including a handling frame and front and back flexible plastic films.

FIG. 2 is a front elevational view of the mold.

FIG. 3 is a top elevational view of the mold.

FIG. 4 is a bottom elevational view of the mold.

FIG. 5 is a left-side elevational view of the mold.

FIG. 6 is a right-side elevational view of the mold.

FIG. 7 is a back elevational view of the mold.

FIG. 8 is a perspective view of a frame for handling an assay matrix.

FIG. 9 is a front elevational view of the handling frame.

FIG. 10 is a top elevational view of the handling frame.

FIG. 11 is a bottom elevational view of the handling frame.

FIG. 12 is a left-side elevational view of the handling frame.

FIG. 13 is a right-side elevational view of the handling frame; and,

FIG. 14 is a back elevational view of the handling frame.
